UNITED STATES PATENT OFFICE.

GEORGE E. RYAN, OF LOS ANGELES, CALIFORNIA, ASSIGNOR TO THE PROSPERITY COMPANY, INC., OF SYRACUSE, NEW YORK, A CORPORATION OF NEW YORK.

SPRING-PAD CONSTRUCTION.

Application filed July 1, 1924. Serial No. 723,575.

This invention relates to spring pads, such as are used on garment and laundry pressing machines, and has for its object a particularly simple and economical spring pad construction by which the springs are secured to the base plate at like ends and at their other ends are secured to the covering for the pad in order to prevent the springs from displacement.

10 The invention consists in the novel features and in the combinations and constructions hereinafter set forth and claimed.

In describing this invention, reference is had to the accompanying drawings in which 15 like characters designate corresponding parts in all the views.

Figure 1 is a fragmentary sectional view of a pad embodying my invention.

Figure 2 is a fragmentary perspective 20 view of the base plate and springs thereon.

Figures 3 and 4 are respectively a fragmentary plan view and an inverted fragmentary plan view of the connection between the springs and the base plate.

25 Figure 5 is a detail view of the rivet connecting the springs to the base plate.

This spring pad construction comprises generally a base plate, coil springs mounted on the base plate, the springs being constructed in pairs and the end coils adjacent the base plate being formed with integral lateral extensions or arms, which overlie the base plate and which continue into the lowermost coil of the other spring of the 35 pair and such connecting arms or extensions are secured between the springs of each pair to the base plate.

Preferably, the springs are arranged in 40 groups, each group comprising a plurality of pairs, each group being here shown as consisting of two pairs arranged with their connecting arms or extensions crossing each other, and such arms being secured to the base plate at their crossing points.

45 The invention, also, includes means forming a part of the spring itself for connecting or interlocking the springs with the covering of the pad, so that the springs are held from lateral displacement and from 50 shifting relatively to the cover and relatively to the base plate.

Spring pads, such as are used in garment and laundry pressing machines, comprise generally a base plate, coil springs mounted 55 on the base plate, and a covering overlying

the upper ends of the springs, the covering consisting of a layer of felt, a wrapper of duck or canvas and layers of other material, and, also, include a top plate, which is perforated, this top plate being usually a sheet 60 of fine wire mesh.

As the pads are usually mounted on the lower buck of a pressing machine, it is more convenient to consider the springs as projecting upwardly from the base plate, although it will be understood that the pad may be used on the upper press head, in which case, the springs will project downwardly from the base plate, or in some other instances the pad may be mounted on the 70 periphery of a drum or cylinder.

1 designates the base plate, 2 are the springs mounted on the base plate and secured at their lower ends thereto, and 3 designates generally the covering and wrapper including the perforated or wire mesh plate 4 overlying the upper ends of the 75 springs.

The springs 2 are arranged in pairs and the lower coils of the springs of each pair, that is, the coils resting on the base plate are formed with lateral or tangential extensions or arms 5, which arms are integral with or continue into the lower coil of the other spring of the pair. These arms or 80 extensions 5 are secured between the springs to the base plate 1. Preferably, the springs are arranged in groups consisting of two pairs of springs and the arms or extensions 5 are arranged, so that they cross and are 85 secured to the base plate at their crossing points.

Preferably, the arms or extensions 5 are secured to the base plate by means of a rivet 6 provided with prongs 7, here shown as 90 four in number, the prongs being arranged astride the arms 5 at their intersecting points and extending through a hole 8 in the base plate and have their ends clinched at 9 on the lower face of the base plate. Thus, a 100 plurality of springs is attached to the base plate in one operation.

The springs are interlocked with the covering and held from lateral displacement at their upper ends by interlocking the end coils with the covering or with the wire mesh 4. As here shown, the upper end coils are formed with upwardly extending prongs or shoulders 10, which interlock with or 105 hook into the covering or which extend into 110

the perforations or interstices of the wire mesh.

This pad is particularly simple and economical in construction, in that a plurality of springs can be attached at the base plate in one operation and further, in that the springs automatically interlock and hook into the covering or the wire mesh when the covering or wire mesh is applied to the 10 upper end of the springs.

What I claim is:

1. A spring pad construction, comprising a base plate, a group of springs, each group comprising a plurality of pairs of springs, 15 the end coil of one spring of each pair having a lateral extension continuing into the end coil of the other spring of the pair, such extensions of the plurality of pairs crossing each other, and means for connecting said extensions to the base plate at their 20 crossing point, said means comprising a

rivet formed with a head and prongs projecting from the head, the prongs being arranged astride the extensions at their crossing point and extending through the 25 base plate and clinched thereto and a covering over the upper ends of the springs.

2. A spring pad construction for pressing machines comprising a base plate, coiled springs mounted on the base plate and having outward extensions of their lower coils 30 overlying the plate, and means for securing said extensions to the plate, a covering over the upper ends of the springs, the springs having means selfcontained therewith for 35 hooking into the covering and thus holding the springs from lateral movement.

In testimony whereof, I have hereunto signed my name, at Syracuse, in the county of Onondaga, and State of New York, this 40 10 day of June 1924.

GEORGE E. RYAN.
